[57] CLAIM

The ornamental design for a combined hardware press and punch machine, substantially as shown and described.

DESCRIPTION

FIG. 1 is a front elevational view of a combined hardware press and punch machine showing my new design; FIG. 2 is a side elevational view taken from the right of FIG. 1;

FIG. 3 is a side elevational view taken from the left of FIG. 1;

FIG. 4 is a rear elevational view thereof;

FIG. 5 is a top plan view thereof; and

FIG. 6 is a bottom plan view thereof.
